(57) **CLAIM**

The ornamental design for a movement assistance device for an orthosis, as shown and described.

DESCRIPTION

FIG. 1 is a top, right, front perspective view of a movement assistance device for an orthosis showing our new design; FIG. 2 is a top, left, rear perspective view thereof.

In FIGS. 1 and 2, the dot-dash broken lines depicting the orthosis is for the purpose of illustrating solely environmental and supplementary structure, and forms no part of the claimed design.

FIG. 3 is an enlarged top, right, front perspective view of the movement assistance device for an orthosis shown in FIGS. 1 and 2;

FIG. 4 is a front elevation view thereof;

FIG. 5 is a rear elevation view thereof;

FIG. 6 is a left elevation view thereof;

FIG. 7 is a right elevation view thereof;

FIG. 8 is a top plan view thereof; and,

FIG. 9 is a bottom plan view thereof.

The uniform dashed broken line showing in FIGS. 1-9 is for the purpose of illustrating portions of the movement assistance device for an orthosis, and forms no part of the claimed design.
